(57) **CLAIM**

The ornamental design for an electric vehicle for infants as shown and described.

DESCRIPTION

FIG. 1 is a perspective view of the electric vehicle for infants according to the present invention.

FIG. 2 is a front view of the electric vehicle for infants of FIG. 1.

FIG. 3 is a rear view of the electric vehicle for infants of FIG. 1.

FIG. 4 is a left side view of the electric vehicle for infants of FIG. 1.

FIG. 5 is a right side view of the electric vehicle for infants of FIG. 1.

FIG. 6 is a top view of the electric vehicle for infants of FIG. 1; and,

FIG. 7 is a bottom view of the electric vehicle for infants of FIG. 1.

The broken lines are shown for the purpose of illustrating portions of the article that form no part of the claim.
